US00D838782S

(12) United States Design Patent (10) Patent No.: US D838,782 S
Brown (45) Date of Patent: * Jan. 22, 2019

(54) CHEER STICK

(71) Applicant: Derrick S. Brown, Suwanee, GA (US)

(72) Inventor: Derrick S. Brown, Suwanee, GA (US)

() Term: 15 Years

(21) Appl. No.: 29/565,699

(22) Filed: May 24, 2016

Related U.S. Application Data

(63) Continuation-in-part of application No. 14/444,930, filed on Jul. 28, 2014, now abandoned.

(57) CLAIM

The ornamental design for a cheer stick, as shown and described.

DESCRIPTION

FIG. 1 is a perspective view showing my new design.

FIG. 2 is an elevational view thereof.

FIG. 3 is an elevational view rotated 90 degrees from FIG. 2.

FIG. 4 is a top plan view thereof; and,

FIG. 5 is a bottom plan view thereof.

The broken lines are included for the purpose of illustrating portions of the article that forms no part of the claimed design.

1 Claim, 2 Drawing Sheets
